UNITED STATES PATENT OFFICE.

ARTHUR LEWIN, OF NEW YORK, N. Y., ASSIGNOR TO KUPFER BROS. CO., OF NEW YORK, N. Y., A CORPORATION OF NEW YORK.

DESIGN FOR WRAPPING PAPER.

Application filed June 16, 1927. Serial No. 22,462. Term of patent 7 years.

To all whom it may concern:

Be it known that I, ARTHUR LEWIN, a citizen of the United States of America, residing in New York, county and State of New York, have invented a new, original, and ornamental Design for Wrapping Papers, of which the following is a specification, reference being had to the accompanying drawing, forming part thereof, in which the figure is a plan view of a piece of wrapping paper showing the design.

I claim:

The ornamental design for wrapping paper as shown.

ARTHUR LEWIN.
